UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

GUARD-RAIL BRACE.

Application filed August 17, 1921. Serial No. 493,099.

To all whom it may concern:

Be it known that I, HAROLD G. WARR, a citizen of the United States, residing at Park Ridge, in the county of Cook and 5 State of Illinois, have invented certain new and useful Improvements in a Guard-Rail Brace, of which the following is a specification.

My invention relates to a guard rail 10 brace and has for its principal object to provide an improved bracing structure of this character which will maintain a guard rail in its proper position with relation to the point of a rail frog so as to prevent the 15 flanges of locomotive or car wheels, when crossing the frog, from striking the relatively sharp point of the frog.

Prior to my invention it has been customary to arrange a guard rail opposite a rail 20 frog and to maintain it in a fixed position with relation to the "outside" running rail, by clamping the same to said running rail. Such construction is not considered entirely satisfactory for the reason that the 25 thrusts of the flanged portion of the wheels against the guard rail and the various strains to which the running rails are subjected, during the passing of traffic, sometimes result in displacing the guard rail 30 with relation to the rail frog. If such displacement of the running rails or frog results in reducing the distance between the frog and guard rail, derailment of a car or other serious damage may result from the 35 flanged portion of a wheel striking the point of the frog. With my invention, I aim to overcome the above and other incidental objections by supporting the guard rail independently of the "outside" running 40 rail by means of a rigid bracing structure extending from the rail frog to the guard rail so as to maintain the guard rail in a fixed position with relation to the rail frog and to further provide said bracing structure with means whereby the distance between said rail frog and guard rail may be 45 accurately adjusted to compensate for wearing away of the outer face of the guard rail.

A preferred embodiment of my invention 50 is illustrated in the accompanying drawing, wherein like characters of reference designate corresponding parts, and wherein:

Fig. 1 is a plan view of a portion of a railway track crossing showing a guard rail 55 brace constructed in accordance with my

invention, applied in its operative position between the rail frog and the guard rail, and

Fig. 2 is a perspective sectional view taken on line 2—2 of Fig. 1.

In the drawing 10 designates one of the 60 running rails of a main railway track, 11, 11^a sections of the running rail at the opposite side of the main track, and 12, 12^a sections of one of the running rails of another track, for example, a side track, which intersects the running rail 11, 11^a of the main track. A rail frog of any suitable construction is positioned at the point of intersection of the rails so that the rail sections 11 and 12 will be in alignment with 70 their corresponding sections 11^a, 12^a. The rail frog is designated generally 13 and consists of a substantially V-shaped center structure, diverging rail sections 11^b, 12^b and spacing blocks 15. The center structure is positioned between the diverging ends of the rail sections 11^b, 12^b and is secured together by means of spacing blocks 15 and bolts 16. The outer ends of the center structure connect with the ends of the rail sections 11^a, 12^a and converge at its other end to form the point 14 of the frog. 80

The rails are spiked to cross ties 17 in the usual manner by spikes 18. A guard rail 19 of any suitable form, is likewise secured in its proper position adjacent the running rail 10, in which position the portion of the guard rail nearest the inner edge of the running rail 10, should be arranged directly 85 opposite the point 14 of the frog. If the form of guard rail employed is the same as that shown in the drawing, the point 20 of the guard rail should be on a line drawn through the frog point 14 at right angles to the running rails of the main track, so that the flange of a wheel rubbing against the point 20 of the guard rail will insure sufficient inward movement of the wheel on the opposite rail to provide the desired clearance between the flanged portions of the 90 said opposite wheel and the frog point 14. The customary construction, previously referred to, embodying a rigid connection between the guard rail and the running rail, naturally permits a longitudinal movement 95 of the guard rail when the running rail, to which it is attached, is subjected to a creeping action. If the guard rail is of the type shown in the drawing, any longitudinal movement which shifts the point 20 of 100

naturally permits a longitudinal movement 105 of the guard rail when the running rail, to which it is attached, is subjected to a creeping action. If the guard rail is of the type shown in the drawing, any longitudinal movement which shifts the point 20 of 110

the guard rail out of alignment with the point 14 of the rail frog, reduces, in effect, the distance between the frog point and the outer surface of the guard rail and therefore 5 by increases the danger of the flanged portion of a wheel striking the point of the frog. I overcome this objection by avoiding a rigid connection of the guard rail with the running rail 10 so that this running 10 rail, under such conditions, may move with relation to the guard rail. In a bracing construction for guard rails wherein the guard rail is secured to the running rail by means of clamps or other rigid connections, 15 displacement of the running rails, tending to reduce the width of the track, will move the guard rail toward the rail frog. This shifting of the guard rail, and also such other movements as may be produced by the 20 severe pressures and thrusts to which guard rails are subjected, are avoided in my invention by rigidly connecting the guard rail to the frog side of the track so that it is, in effect, a part of the rail frog, thereby 25 maintaining the guard rail in a fixed position with relation to the rail frog.

The brace structure, as shown in the drawing, consists preferably of an inverted channel shaped bar 21 fitted over one of the 30 cross ties 17 and extending across the track, preferably, on a line drawn through the point 14 of the frog 13 at right angles to the running rails of the main track. The ends of the channel bar preferably extend 35 under the running rail 10 and the frog 13 so as to function as metal wearing pads at these points. The guard rail 19 is located adjacent the running rail 10 in its proper position with relation to the point 14 of the 40 rail frog and is secured to the channel 21 by means of a brace casting 22 or other suitable fastening device adapted to hold the base flange 23 against an upturned abutment 24 formed on the channel bar. The 45 brace casting is preferably formed to fit the contour of the base flange 25 and vertical web 26 of the guard rail, and is bolted to the web of the rail and to the web 27 of the channel bar by bolts 28, 29, respectively. 50 The ends of the guard rail may be attached to the cross ties 17 in any approved manner, for example, by spikes 30. The frog structure at the opposite side of the track-way is secured to the channel bar 21 preferably 55 with means for effecting an adjustment of the channel bar transversely of the track so as to permit the position of the guard rail to be accurately adjusted when applied or when it is necessary to shift it to compensate for the wearing away of its outer surface. In the drawing, I have shown this connection as consisting of wedge-shaped clamping plates 31 formed with angularly disposed lips 32 which overlap the 60 base flanges of the rail sections 11, 12, and 65

adapted to be driven between said base flanges and a plurality of abutments 33 formed on the web 27 of the channel bar on opposite sides of the frog structure. The clamping plates 31, 31 are preferably 70 formed with a plurality of squared holes 34 and the channel bar is formed with relatively long slots 35, 35 so that the plates 31, 31 may be driven to their wedging positions and secured in such position by means of 75 spikes 36 driven into the cross tie 17. The outer end of the channel bar, adjacent the running rail 10 is provided with slots 37, 38, through which the spikes 39, 40 for the rail 10 are driven into the cross tie. 80

By using a cross brace, channel shaped in cross-section, the vertical flanges 41, 41 rigidify the brace so as to make it practical to use a channel bar having a relatively thin web 27, whereby the abutments 24, 33 85 may be conveniently formed by slitting the web 27 of the channel bar, as indicated at 42, in Fig. 2, and then extending the tongue portion of the slits upward. The flanges 41, 41 also rigidify the brace member 90 adjacent the rails so that the portion of the channel bar intervening between the upper face of the cross tie 17 and the base flanges of the rails will not be bent upward by the heavy pressure of the traffic. 95

In the drawing, I have illustrated my invention in connection with a main track-way, though it will be obvious that the frog 13 may, if desired, be connected to the guard rail of the side track by extending the end 100 43 of the channel bar or by providing a separate brace structure similar to that shown in the drawing.

I claim:

1. The combination with a frog structure, 105 of a railway track and a guard rail arranged adjacent a running rail at the opposite side of the track with capacity for relative movement of said guard and running rails, of means for securing said guard rail in fixed position with relation to the point of the frog so that said running rail may move without disturbing the position of said guard rail with relation to said frog and so that lateral movement of the guard rail imparts a corresponding movement to the frog 115 structure.

2. The combination with a frog structure of a railway track and a guard rail arranged adjacent a running rail at the opposite side of the track with capacity for relative movement of said guard and running rails, of means for securing said guard rail in fixed position with relation to the point of the frog so that said running rail may move 120 without disturbing the position of said guard rail with relation to said frog and so that movement of either the guard rail or frog structure imparts a corresponding movement to the other. 125

3. The combination with a frog structure of a railway track, and a guard rail arranged adjacent a running rail at the opposite side of the track with capacity for relative movement of said guard and running rails, of means for securing said guard rail in fixed position with relation to the point of the frog comprising a rigidifying member movable independently of said running rail and extending transversely of the track and secured to said guard rail and frog structure.

4. The combination with a frog structure of a railway track and a guard rail arranged at the opposite side of the track, of means for securing said guard rail in fixed position with relation to the point of the frog comprising a rigidifying member movable independently of said running rail and extending transversely of the track and secured to said guard rail and frog structure with capacity for adjustment.

5. The combination with a frog structure of a railway track and a guard rail arranged at the opposite side of the track, of means for securing the guard rail in fixed position with relation to the point of the frog comprising a rigidifying member extending transversely of the track, means for securing said guard rail to said rigidifying member, and means for adjustably securing said rigidifying member to said frog structure.

6. The combination with a frog structure of a railway track and a guard rail arranged at the opposite side of the track, of means for securing the guard rail in fixed position with relation to the point of the frog comprising an inverted channel-shaped rigidifying member adapted to be fitted over one of the cross-ties of the track-way, and extending transversely of the track, means for securing said guard rail to said rigidifying member, and means for adjustably securing said rigidifying member to said frog structure.

7. The combination with a frog structure of a railway track and a guard rail arranged at the opposite side of the track, of means for securing the guard rail in fixed position with relation to the point of the frog comprising an inverted channel-shaped rigidifying member adapted to be fitted over one of the cross-ties of the track-way and extending transversely of the track on a line through the point of the frog at right angles to the running rails, means for securing said guard rail to said rigidifying member, and means for adjustably securing said rigidifying member to said frog structure.

8. The combination with a frog structure of a railway track and a guard rail arranged at the opposite side of the track, of means for securing the guard rail in fixed position with relation to the point of the frog com-

prising an inverted channel-shaped, rigidifying member adapted to be fitted over one of the cross-ties of the track-way and extending transversely of the track at right angles to the running rails and intervening between said cross-tie and the running rail, guard rail and frog structure, respectively, means for securing said guard rail to said rigidifying member, and means for adjustably securing said rigidifying member to said frog structure.

9. The combination with a frog structure of a railway track and a guard rail arranged at the opposite side of the track, of means for securing the guard rail in fixed position with relation to the point of the frog comprising an inverted channel-shaped, rigidifying member adapted to be fitted over one of the cross-ties of the track-way and extending transversely of the track on a line drawn through the point of said frog at right angles to the running rails, and means for securing said rigidifying member to the guard rail and frog structure with capacity for relative adjustment as between the said guard rail and frog structure.

10. The combination with a frog structure interposed in a rail at one side of a railway track and a guard rail arranged adjacent the running rail at the opposite side of the track, of means movable independently of said running rail for securing said guard rail in fixed position with relation to said frog structure whereby said running rail may move with relation to the guard rail without affecting the position of the guard rail with relation to said frog structure.

11. The combination with a frog structure interposed between rail sections at one side of a railway track and a guard rail arranged adjacent a running rail at the opposite side of the track, of means for securing said guard rail in fixed position with relation to said frog structure with capacity for relative movement between the guard rail and said running rail comprising a transverse rigidifying member extending under the running rail and frog structure, and means for securing said guard rail and said frog structure to said rigidifying member.

12. The combination with a frog structure of a railway track and a guard rail, of means for securing the guard rail to said frog structure comprising a rigidifying member extending transversely of the track, and means for attaching the guard rail to the rigidifying member comprising a brace engaging the vertical web of the rail and secured to said rigidifying member.

13. The combination with a frog structure of a railway track and a guard rail, of means for securing said guard rail to said frog structure comprising a rigidifying member extending transversely of the track, and means for attaching the guard rail to the

rigidifying member comprising a brace conforming to the contour of the vertical web and one of the base flanges of the rail and secured to said rigidifying member.

- 5 14. The combination with a frog structure of a railway track and a guard rail, of means for securing the guard rail to the frog structure comprising an inverted channel bar extending across the track and under the base 10 flange of said guard rail and formed with an upstanding portion providing an abutment for the outside flange of the guard rail base, means for securing the guard rail to said channel bar comprising a cast metal 15 brace member conforming to the contour of the vertical web and inner base flange of the guard rail, secured to the guard rail and to said channel bar, and means for adjustably securing said channel bar to said frog structure. 20

15. The combination with a frog structure of a railway track and a guard rail, of means for securing the guard rail to the frog structure comprising an inverted channel bar extending across the track, means for attaching the guard rail to said channel bar, and means for adjustably securing said channel bar to the frog structure comprising a wedge member adapted to be driven between said 25 30 frog structure and an abutment on said channel bar.

16. The combination with a frog structure of a railway track and a guard rail, of means for securing the guard rail to the frog structure comprising an inverted channel bar extending across the track, means for attaching the guard rail to said channel bar, and means for adjustably securing said chan- 35

nel bar to the frog structure comprising wedge members on opposite sides of the frog structure adapted to be driven between said frog structure and abutments formed on said channel bar. 40

17. The combination with a frog structure of a railway track and a guard rail, of means for securing the guard rail to the frog structure comprising an inverted channel bar extending across the track, means for attaching the guard rail to said channel bar, and means for adjustably securing said channel bar to the frog structure comprising wedge members on opposite sides of the frog structure adapted to be driven between said frog structure and abutments formed on said channel bar; said wedge members and channel bar being formed with oppositely disposed openings for receiving rail spikes whereby said wedge members may be secured in their wedging position by rail spikes driven into the cross-ties. 45 50 55

18. A bracing structure of the character described, comprising a channel bar adapted to be fitted over a cross-tie and extend under the running and guard rails at one side of the track, and under a rail frog structure at the opposite side of the track, means for securing the guard rail structure to the channel bar, and means for securing the rail frog construction to the channel bar; the portion of said channel bar adjacent the guard rail being provided with spike slots whereby the said running rail may be spiked to said cross-tie with capacity for movement with relation to the guard rail. 60 65 70

HAROLD G. WARR.
